UNITED STATES PATENT OFFICE.

KURT STOYE, OF FLUSHING, NEW YORK, ASSIGNOR TO THE KNY-SCHEERER CORPORATION OF AMERICA, OF NEW YORK, N. Y., A CORPORATION OF NEW YORK.

BONE SHAPING AND THREADING DEVICE.

Application filed June 7, 1923. Serial No. 643,837.

To all whom it may concern:

Be it known that I, KURT STOYE, a citizen of the United States, residing at 266 Central Avenue, Flushing, Long Island, in the 5 county of Queens and State of New York, have invented certain new and useful Improvements in Bone Shaping and Threading Devices, of which the following is a specification.

10 This invention relates to bone shaping and threading devices, and the novelty consists in the adaptation and arrangement of the parts, as will be more fully hereinafter pointed out.

15 In the treatment of various bone fractures and in the setting of new pieces of bone, which are usually cut from the shin of the person being treated, it is very often found necessary to pin the piece of bone 20 which is being inlaid to the surrounding bone tissue where it is placed in order to assure the inlaid pieces staying in exact position and growing exactly into that position.

25 Many different substances have been tried for pinning together such bone members, including the use of prepared beef bone pins which come prepared and sterilized for this purpose, but which do not readily knit 30 with the human bone as will a piece of bone of the person being treated which is of a finer texture and harder than the beef bone.

35 There has therefore come to be a tremendous demand for a properly threaded pin or screw of human bone for use in pinning together the new bone or inlay with the surrounding bone into which such inlay is placed, and in order to be sure of perfect knitting it is now recognized by the medical 40 profession that it is necessary to use a bone pin or screw taken from the person being treated the same as the inlay is taken usually from the shin of the person being treated.

45 This must all be done under the usual sterile conditions of the operating room, and must be done quickly as the operation is necessarily a long one and every minute counts. My device is adapted to solve this 50 problem, being adapted to shape a piece of bone cut from the person being treated and threading the same in the same device without loss of time and all under the sterile conditions required in such operations.

55 Referring to the drawings, Figure 1 is

a side view of one embodiment of my device; Figure 2 is a top plan view of the device shown in Figure 1 with a portion of the casing cut away in order to show the interior construction. 60

In the drawings 5 is a base member having rigid brackets 6 secured thereto adapted to support and hold rigidly in position a motor 7 of usual construction for the purpose herein stated and having the usual 65 sterilizable and removable shell, which motor receives its source of power from the broken connection shown at 8, which connection can be readily broken by means of the thumb screw 9 operating in the usual 70 manner. At the opposite end of the motor 7 is a driven gear wheel 10 which drives a shaft 11 to which the gear wheel 10 is rigidly secured. The power from the motor shaft being transferred to gear 10 by 75 means of the usual worm construction which is not shown herein. A casing 12 is also mounted on the base 5 by means of a bracket 13 rigidly secured to the casing 12, which is adapted to slide into slots 14 in base 80 brackets 15 which are rigidly secured to the base member 5 at 16.

In the simpler form of my construction shown in Figures 1 and 2 the shaft 11 passes through bearing 13' integral with 85 the casing 12 so that at the outer end said shaft 11 rests in 14' also integral with the casing 12. On the shaft 11 is a worm 15' which meshes with a worm gear 16' which is rigidly secured to a shaft 17 is supported at 90 18 in the casing 12, and on which shaft 17 at the other end is rigidly secured a bevel gear 19 which is a driving gear. Pivoted on a hollow pin 20 supported in one side of the casing 12 is a bevel gear 21 which is 95 always in mesh with the driving gear 19. On the other side of the casing 12 from 20 is another bevel gear 22 which is supported on a hollow pin 23 in the side of the casing 12, and the bevel gear 22 is also 100 in mesh with the driving gear 19 so that gears 21 and 22 always travel in opposite directions because of the driving gear 19 with which they are always in mesh. A shaft 24 is mounted in the hollow pins 20 and 23 so that it will rotate freely therein, and the shaft 24 carries a sleeve 25 integral therewith which has cut-outs 26 and 27 adapted to engage pins 28 and 29 respectively on bevel gears 22 and 21. A shaper 110

or thread cutter 30 may be mounted on the shaft 24 so as to rotate therewith, said shaper or thread cutter being interchangeable.

6 The operation of the construction described and shown is such that as the motor 7 is set in operation the wheel 10 is thereby rotated and the worm drive 15 on the integral shaft 11 is also rotated. The worm 10 drive 15 being in mesh with the worm gear 16 thereby sets that in operation, which in turn causes the rotation of the bevel gear or driving gear 19. As the bevel gear 19 rotates the two bevel gears 21 and 22 which 15 are always in mesh with the driving gear 19 also rotate in opposite directions. With the shaper or thread cutter 30 in position on the shaft 24 as the bone to be shaped or the bone pin to be threaded is pressed 20 into the member 30, the shaft 24 carrying the sleeve 25 will press the sleeve 25 until the cut-out 27 engages the pin 29, whereupon 30 will be driven in the direction of the gear 21. As the bone being cut or 25 threaded is completed the operator as he pulls the same back will cause the shaft 24 and the sleeve 25 to pull outwardly so that the cut-out 26 will register with the pin 28, thereby causing the shaft 24 to 30 rotate in the opposite direction and with the bevel gear 22 thereby turning out the bone pin in its completed shape as a pin or completely threaded as a screw according 35 to which device 30 is in position for use. A dowel shaper 30 may be attached directly to shaft 11 thereby permitting the same to be run at a higher speed than it is possible if mounted as previously described.

40 Thus a threaded pin or bolt of the patient's own bone is quickly and easily prepared under absolutely sterile conditions so that it can be used immediately in securing together the inlaid portion with the 45 surrounding bone material so as to effect a perfect growth of the bone material together in the exact position required.

I claim:

50 1. In an automatic bone cutting machine means for shaping and threading the bone when cut comprising a casing separately attachable to said machine and containing a shaft driven by said machine, a worm gear mounted on said shaft, a second shaft 55 mounted in said casing in a horizontal plane and crosswise of said first shaft, a worm gear mounted on said second shaft so as to mesh with said worm gear, a bevel gear mounted on the outer end of said second 60 shaft, a pair of bevel gears mounted in said machine with said first bevel gear so that they are driven in opposite directions thereby, a bone shaper mounted on a third shaft running through said pair of bevel 65 gears, and means for engaging said third

shaft with either of said pair of gears alternately.

2. In an automatic bone cutting machine means for shaping and threading the bone when cut comprising a casing separately attachable to said machine and containing a shaft driven by said machine, a worm gear mounted on said shaft, a second shaft 70 mounted in said casing in a horizontal plane above and crosswise of said first shaft, a worm gear mounted on said second shaft so as to mesh with said worm gear, a bevel gear mounted on the outer end of said second shaft, a pair of bevel gears mounted in said machine with said first bevel gear 75 so that they are driven in opposite directions thereby, a bone shaper mounted on a third shaft running through said pair of bevel gears, and means for engaging said third shaft with either of said pair of gears 80 alternately, consisting of a sleeve rigidly secured to said shaft having cut-outs adapted 85 to engage pins on said pair of bevel gears.

3. In an automatic bone cutting machine means for shaping and threading the bone when cut comprising a casing separately attachable to said machine and containing a shaft driven by said machine, a worm gear mounted on said shaft, a second shaft 90 mounted in said casing in a horizontal plane above and crosswise of said first shaft, a worm gear mounted on said second shaft so as to mesh with said worm gear, a bevel gear mounted on the outer end of said second shaft, a pair of bevel gears mounted in said machine with said first bevel gear so that they are driven in opposite directions 95 thereby, a bone shaper mounted on a third shaft running through said pair of bevel gears, and means for engaging said third shaft with either of said pair of gears alternately, and a base member adapted to 100 support all.

4. In an automatic bone cutting machine 110 means for shaping and threading the bone when cut comprising a casing separately attachable to said machine and containing a shaft driven by said machine, a worm gear mounted on said shaft, a second shaft 115 mounted in said casing in a horizontal plane above and crosswise of said first shaft, a worm gear mounted on said second shaft so as to mesh with said worm gear, a bevel gear mounted on the outer end of said second shaft, a pair of bevel gears mounted in said machine with said first bevel gear so that they are driven in opposite directions 120 thereby, a bone shaper mounted on a third shaft running through said pair of bevel gears, and means for engaging said third shaft with either of said pair of gears alternately, consisting of a sleeve rigidly secured to said shaft having cut-outs adapted 125 to engage pins on said pair of bevel gears.

gears, and a base member adapted to support all.

5. In an automatic bone cutting machine means for shaping and threading the bone when cut comprising a casing separably attachable to said machine and containing a shaft driven by said machine, a second shaft having a bevel gear, said shaft being driven by suitable means from the first shaft, a third shaft carrying a pair of bevel gears mounted in mesh with said bevel gears so that they are driven in opposite directions thereby, a bone shaper mounted on a shaft running through said pair of bevel gears, and means for engaging said bone shaper shaft with either of said pair of gears alternately.

6. In an automatic bone cutting machine

means for shaping and threading the bone when cut comprising a casing separably attachable to said machine and containing a shaft driven by said machine, a second shaft having a bevel gear, said shaft being driven by suitable means from the first shaft, a third shaft carrying a pair of bevel gears mounted in mesh with said bevel gears so that they are driven in opposite directions thereby, a bone shaper mounted on a shaft running through said pair of bevel gears, means for engaging said bone shaper shaft with either of said pair of gears alternately, and a base member adapted to support all.

In testimony whereof I affix my signature.

KURT STOYE.
